UNITED STATES PATENT OFFICE.

WILLIAM B. VAN BUREN, OF BROOKLYN, NEW YORK.

DESIGN FOR A BOX.

SPECIFICATION forming part of Design No. 25,643, dated June 16, 1896.

Application filed April 6, 1896. Serial No. 586,454. Term of patent 7 years.

To all whom it may concern:

Be it known that I, WILLIAM B. VAN BUREN, a citizen of the United States, residing in the city of Brooklyn, in the county of Kings and State of New York, have invented and produced a new and original Design for Boxes, of which the following is a specification, reference being had to the accompanying drawings, in which—

10 Figure 1 represents a top or front view of a box of my design, and Fig. 2 represents a section in the line 2 2 of Fig. 1.

15 My design consists in a novel form and configuration of the partitions which divide the box into compartments. The external form of the box as represented is quadrangular. It contains straight partitions *a*, represented as of a depth less than that of the box and extending between two opposite sides. On

20 opposite sides of each of these partitions are shorter partitions *b* of bow form. Similar partitions *b* of bow form are arranged against those sides of the box with which the straight partitions are parallel, the box being thus divided into compartments *A A* and *B B*, the 25 end portions of the said compartments *A A* being square and their sides contracted toward each other in curved form and the compartments *B B* each being of the form of a segment, one side being straight and one side 30 curved.

What I claim is—

The design for a box, substantially as herein shown and described.

WILLIAM B. VAN BUREN.
